UNITED STATES PATENT OFFICE

WALTER F. SEIDEL, OF CHICAGO, ILLINOIS

DESIGN FOR A CAKE ORNAMENT OR SIMILAR ARTICLE

Application filed December 8, 1931. Serial No. 42,000. Term of patent 14 years.

To all whom it may concern:

Be it known that I, WALTER F. SEIDEL, a citizen of the United States, residing at Chicago, Cook County, Illinois, have invented a new, original, and ornamental Design for Cake Ornament or Similar Article, of which the following is a specification, reference being had to the accompanying drawing forming part thereof, in which the figure is a perspective view of a cake ornament or similar article, showing my new design.

I claim:

The ornamental design for a cake ornament or similar article as shown.

WALTER F. SEIDEL.
